CLAIM

The ornamental design for a decanter set, as shown and described.

DESCRIPTION

FIG. 1 is a front and top perspective view of a decanter set, showing our new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view thereof, shown in a using position.

The broken lines in the figures illustrate portions of the decanter set that form no part of the claimed design. The broken lines showing of two wine glasses in FIG. 9 depict environmental structure that form no part of the claimed design.
